[57] CLAIM

The ornamental design for a mail box, substantially as shown and described.

DESCRIPTION

FIG. 1 is a front elevational view of my new design for a mail box illustrating the construction as being that of wood.

FIG. 2 is a rear elevational view thereof;

FIG. 3 is a side elevational view, the opposite side presenting a mirror image;

FIG. 4 is a bottom plan view thereof; and

FIG. 5 is top plan view thereof.

The essential features of my design reside in the portions shown in solid lines, conventional ornaments a part thereof being shown in FIGS. 1 and 4.

FIG. 1

FIG. 3

FIG. 4

FIG. 5
